(57) **CLAIM**

The ornamental design for a bottle, as shown and described.

DESCRIPTION

FIG. 1 is a top and front side perspective view of a bottle, showing my new design;

FIG. 2 is a left side elevational view thereof, the right, front and back side elevational views being identical;

FIG. 3 is a top plan view thereof;

FIG. 4 is a bottom plan view thereof;

FIG. 5 is a top and front side perspective view of a second embodiment of my new design for a bottle;

FIG. 6 is a left side elevational view thereof, the right, front and back side elevational views being identical;

FIG. 7 is a top plan view thereof; and,

FIG. 8 is a bottom plan view thereof.
